(57) **CLAIM**

We claim the ornamental design for a pocket case for a mobile communications device, as shown and described.

DESCRIPTION

FIG. 1 is a front, left-side, and bottom perspective view of a pocket case for a mobile communications devices according to the present design.

FIG. 2 is a back, right-side, and top perspective view thereof.

FIG. 3 is a front plan view thereof.

FIG. 4 is a back plan view thereof.

FIG. 5 is a right-side elevation view thereof.

FIG. 6 is a left-side elevation view thereof.

FIG. 7 is a top elevation view thereof; and,

FIG. 8 is a bottom elevation view thereof.

The broken lines throughout the drawing figures form no part of the claimed design and depict an environmental mobile communications device and portions of the pocket case for a mobile communications device that form no part of the claimed design.

1 Claim, 3 Drawing Sheets
